CLAIM

The ornamental design for a rail mountable gun light with rotationally keyed mount assembly, as shown and described.

DESCRIPTION

FIG. 1 is a perspective view of an ornamental design for a rail mountable gun light with rotationally keyed mount assembly;

FIG. 2 is a side view of a first side of the ornamental design; FIG. 3 is a side view of a second side of the ornamental design; and,

FIG. 4 is an end view of the ornamental design. The broken lines in the drawings disclose the unclaimed portions of the rail mountable gun light with rotationally keyed mount assembly only, and form no part of the claimed design.
